UNITED STATES PATENT OFFICE

KRISTIAN A. JUTHE, OF NEWTON, AND ALBERT J. HANSON, OF ARLINGTON, MASSACHUSETTS, ASSIGNORS TO AMERICAN ELECTRIC FURNACE COMPANY, OF BOSTON, MASSACHUSETTS, A CORPORATION OF MASSACHUSETTS

APPARATUS FOR SUPPLYING HEATED OIL

Application filed January 3, 1928. Serial No. 244,288.

This invention relates to a method of and means for heat-treating steel castings and the like by providing a bath of heated liquid in which the castings may be immersed, and heating the liquid for the bath at a point outside the bath. An object of the invention is to provide means for automatically controlling the temperature of the bath by the circulation of heated oil therethrough, and to safeguard the apparatus against overheating. In carrying out the invention, means are provided for circulating liquid, such as oil, around a system which includes a tank for the treating bath and a furnace for reheating the oil drawn from the bath and reintroducing the heated oil into the bath. The temperature of the oil entering the bath is regulated automatically by means responsive to temperature conditions in the bath for controlling the operation of the furnace. Means for safeguarding the apparatus from overheating include a thermostatic device in the pipe line leaving the furnace for cutting off the heat when the oil leaving the furnace exceeds a predetermined temperature, and apparatus for automatically cutting off the heat if the circulating pump stops.

Another object of the invention is to supply heated oil with or without additional cool oil simultaneously to a plurality of baths of independent temperatures, the oil supply to each being automatically controlled to maintain the several temperatures of the different baths. Various other advantageous features of the invention will be apparent to one skilled in the art from the following description of the invention and from the drawings, of which,—

Figure 1 is an elevation of apparatus embodying the invention, a portion being shown in section.

Figure 2 is a section on the line 2—2 of Figure 1.

Figure 3 is a plan view of the apparatus shown in Figure 1.

Figure 4 is a side elevation of the furnace, the walls being in section to show the arrangement of parts inside.

Figure 5 is a fragmentary section on the line 5—5 of Figure 4.

Figures 6 and 7 illustrate modified forms of furnaces for heating liquid.

Figure 8 is a diagram of wiring which may be used in connection with the apparatus shown in Figure 1.

Figures 9 and 10 show diagrammatically, arrangements of apparatus for regulating the temperature in a plurality of tanks by the supply of liquid thereto.

Referring to the drawings in detail, 10 represents a work-treating tank which is adapted to receive hot liquid such as oil. This tank is preferably lagged with heat-insulating material and may be provided with a removable cover 11. Among the uses of a tank of this kind in industry is its employment to hold hot oil into which steel castings and the like may be dipped in order to draw their temper to the desired extent after having been heated and quenched to hardness. As indicated in Figure 1, a suitable basket or receptacle 12 may be provided to hold the work which is inserted into the tank for treatment. The tank 10 may be divided into two compartments 13, 14 as by a partition 15 which extends upwardly from the bottom of the tank to a level near but below the top thereof. In the compartment 13 a perforated plate 16 may be secured in a horizontal position dividing the compartment into upper and lower chambers. This plate 16 serves as a false flooring to take the weight of the basket 12 and to protect apparatus parts located in the lower chamber 17. In order to supply heated oil or other suitable liquid to the tank 10, a furnace 18 may be provided, this furnace containing one or more coils of pipe 19 and a plurality of heating units 20. Each coil 19 is connected to a delivery pipe 21 which enters the tank 10 and terminates at its delivery end in the chamber 17. As shown, the delivery end may consist of a series of horizontally disposed pipes 22 having perforations distributed thereover so that the heated oil enters the tank at a multiplicity of spaced points within the chamber 17. The oil introduced into the chamber 17 intermixes with the oil already there and this mixture is forced through the perforations of the plate 16 into the work-containing

100

portion of the compartment 13 so that a constant upward flow is maintained through this compartment. As heated oil is introduced into the chamber 17, an equal amount of oil 5 overflows into the chamber 14 which acts as a sump and communicates at its lower end with a drain pipe 23 which extends to a pump 24 driven as by a suitable motor 25 through reduction gearing 26. The oil which is drawn 10 from the sump 14 through the pipe 23 is sent through a pipe 27 to the furnace 18 where it is reheated as it flows through the coil 19 and continues on through the supply pipe 21, thus returning to the tank 10. A storage tank 28 15 may be provided having a connection 29 through which oil may be drained from the compartment 13 when it is desired to empty this compartment, and a connection 30 from the bottom of the storage tank to the pump 24 by which oil may be drawn from this tank during the operation of the apparatus to replenish oil which may leak out or otherwise be lost.

The furnace 18, as previously described, 25 preferably contains one or more coils of pipe 19 (one being shown) through which the oil flows. As shown in Figures 4 and 5, the furnace 18 may conveniently comprise a cylindrical casing lagged with heat-insulating material, the coil 19 being arranged therein closely adjacent to the side walls thereof. Within the coil 19 the heating units 20 are arranged as desired. The heating units may comprise elongated slabs of heat- 30 resistant material having notches in their edges to receive a ribbon 31 of resistance metal which may be wound thereon. A number of these heating elements may be arranged to extend radially edgewise within 35 the coil 19 as illustrated in Figure 5. This arrangement of parts minimizes mutual heating between the turns of the ribbon 31 on the units and between the several units themselves so that a larger current may be passed 40 through the units without endangering the ribbons 31. Modified forms of heating elements are illustrated in Figures 6 and 7, the former showing a series of tiles 32 having 45 grooves to receive coils of resistance wire 33. The tiles 32 are supported in such a way that 50 the coils are held opposed to the pipe coil 19 so that the hot wires 33 will radiate directly against the pipes. In the form of heater shown in Figure 7, a cylinder 34 of heat- 55 resistant material is inserted within the pipe coil 19, the outer diameter of this cylinder being slightly less than the inner diameter of the coil 19. The cylinder may be provided with a series of peripheral grooves 60 in which are located resistance elements 36 which may consist of suitable metal ribbon or wire bent in the zigzag form as shown. The several resistance elements 36 may be 65 connected up as desired in series parallel or

otherwise according to the resistance of each element and the voltage supplied.

In order to regulate the temperature of the coil in the chamber 13, means is provided for controlling the furnace 18 so that the oil 70 which is delivered therefrom to the chamber 17 may be at a suitable temperature to maintain the pool of oil in the compartment 13 at the desired temperature. To this end, a heat-responsive element 37 may be located at 75 any desired point within the compartment 13. As shown, the element 37 is located within the chamber 17 and communicates with a thermostatic device 38 by which the electric current supplied to the furnace 18 is automatically turned on and off in accordance with the temperature conditions in the chamber 17. The apparatus by which the current supplied to the furnace 18 is controlled is shown diagrammatically only as it is old and 80 well known in the art.

Figure 8 indicates diagrammatically the wiring plan for connecting the various parts of the apparatus for a two-phase power system. A main switch 39 may be provided to start and stop the motor 25. From the power supplied for the operation of the motor, a shunt circuit may be used to operate a magnetic relay switch 40 which in turn operates a magnetic switch 41 to connect and disconnect the heating elements with a suitable source of current. The shunt circuit for operating the relay switch 40 may be also controlled by a hand switch 42. In order to protect the apparatus from excessive heating, a safety thermostat 43 is inserted in the supply pipe 21, this thermostat acting when the oil reaches a predetermined temperature to open the switch 40 and thereby the switch 41, cutting off the current from the furnace 18. As a further protective measure, provision is made for automatically rendering the furnace inoperative upon failure of the liquid circulating means. For example, if an electric furnace is used, it may be controlled by 100 connections as shown in Figure 8. As there- 105 in shown, the shunt circuit containing the relay switch 40 is hooked up to the wires carrying one of the phases of the current for driving the motor 25. If this phase fails, the relay switch 40 will open at once, its energizing current being cut off. If the other phase fails, the extra load on the first phase circuit will burn out fuses at the switch 39 and thereby cause the opening of the relay switch 40. In any case, opening of the switch 40 results 110 at once in the opening of the magnetic switch 41 and consequently in the cutting off of the current supplied to the furnace 18. The apparatus used in thus controlling the heat supplied to the oil in the furnace is per se no part 115 of this invention.

In addition to the heating of a single bath of liquid by the regulated introduction of heated liquid thereinto, the invention in-

cludes the heating of a plurality of baths of liquid to independent and separately controlled temperatures by the utilization of heated liquid from heating means which heat the liquid at a point outside of the baths. The utilization of heated liquid from a common and separate heater may be accomplished in a number of ways, two of which are shown on the drawings by way of example.

10 Figure 9 illustrates a method of maintaining a plurality of tanks at any desired independent temperatures. The apparatus shown in this figure and in Figure 10 is conventionally and diagrammatically indicated. The 15 pump 24 sends oil to the furnace 18 where the oil is heated to a desired temperature above that of the hottest treating tank. From the furnace 18 the hot oil is sent through a distributing pipe 44 from which 20 the oil branches to the separate tanks. Each branch pipe is supplied with an automatic valve 45 which is controlled by a suitable thermostat 46 responsive to temperature conditions within the tank. The mechanism by 25 which the oil supply is controlled through the actuation of the automatic valves 45 is old and well known in the art, and per se forms no part of this invention. The valves 45 are so operated as to admit hot oil in sufficient 30 quantities to maintain the desired temperature in each individual tank. The oil not required for the tanks is by-passed to a discharge pipe 47 through a loaded relief valve 52 by which sufficient working pressure may 35 be maintained in the supply line 44 and which insures a constant movement of oil through the furnace 18 so as to prevent overheating or carbonization of the oil. The oil entering the tanks passes through eventually 40 and leaves by a discharge connection 50 which communicates with the pipe 47. The latter leads to a suitable sump tank 48 from which the oil passes to the pump 24 through a pipe 49.

45 Figure 10 shows a slightly different arrangement of apparatus for accomplishing the same result. In this arrangement, the pump 24 forces oil into the furnace 18 from which it is sent through a supply pipe 44 by 50 suitable branches to the several tanks. In order to regulate the temperature of the tanks, comparatively cool oil is simultaneously supplied from the sump tank 48 as by a pump 55 through a supply pipe 56, this cooler oil being mixed with the hot oil in an automatically regulated mixing valve 55 as it enters each tank, the valve 55 being controlled by a 55 thermostatic device 46 responsive to temperature conditions at any desired point in the tank. As in the apparatus shown in Figure 60, a relief valve 52 and a return pipe 47 is provided to insure constant movement of the oil through the furnace. If the pump 51 be 65 centrifugal or any other type incapable of

building up excessive pressures, there need be no return pipe for the cool oil.

Having thus described certain embodiments of this invention, it should be evident to those skilled in the art that various changes and modifications might be made therein without departing from its spirit or scope as defined by the appended claims.

We claim:—

1. Apparatus of the class described, comprising a liquid container having a partition therein extending part way to the top thereof and dividing said container into two compartments, a perforated baffle plate extending horizontally across one of said compartments above the bottom thereof and forming a chamber in the lower portion of said compartment, means for introducing heated liquid into said chamber whereby liquid rises through said baffle plate and spills over said partition into the other compartment, a discharge pipe connecting with said other compartment, and means for heating liquid prior to its introduction into said chamber.

2. Apparatus of the class described, comprising a liquid container, a partition extending part way up within said container and dividing it into two compartments, means for withdrawing liquid from the lower portion of one of said compartments and for reintroducing the liquid into the container at the bottom of the other compartment, a perforated plate extending horizontally across said other compartment forming chambers above and below said plate, means for heating the liquid withdrawn from the container prior to its reintroduction thereinto, and means responsive to temperature conditions in said other compartment for regulating said heating means.

3. Apparatus of the class described, comprising a closed tank having a removable cover, a partition extending part way up from the bottom of the tank and dividing the tank into two compartments, a perforated plate extending horizontally across one of said compartments forming a chamber in the lower portion of said compartment, a supply pipe entering said chamber having a perforated end section, a pump, a pipe extending from said other compartment to said pump, a heater including electric heating units, a pipe extending from said pump through said heater and connecting with said supply pipe, and means responsive to temperature conditions in said chamber for controlling the current supply to said heating units.

4. Apparatus for heat-treating steel castings, comprising a tank for hot liquid, a furnace containing a pipe coil and an electric heating unit, a pump, piping connecting said tank, pump and coil for continuous circulation of liquid therethrough, a thermostatic element in said tank near the supply pipe,

means responsive to said element for regulating said electric unit, a second thermostatic element in the pipe between the coil and the tank, and means responsive to said second element for cutting off the current from said electric unit when the liquid in the pipe between the coil and tank exceeds a predetermined temperature.

5. Apparatus for heat-treating metal objects, comprising a tank for hot liquid, means outside of said tank for heating liquid, a pump, piping connecting said tank, pump and heating means for continuous circulation of liquid therethrough, a thermostatic element in said tank, means responsive to said element for regulating said heating means, a second thermostatic element in the pipe between the heating means and the tank, and means responsive to said second element for rendering the heating means inoperative when the liquid in the pipe containing said second element exceeds a predetermined temperature.

In testimony whereof we have affixed our signatures.
